[57] CLAIM

The ornamental design for chuck of an industrial robot, as shown and described.

DESCRIPTION

FIG. 1 is a bottom and front view of chuck of industrial robot showing our new design;

FIG. 2 is a top and rear view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines showing of the body in the figures is for illustrative purposes only and forms no part of the claimed design.
